(57) **CLAIM**

What is claimed is an ornamental design for a headphone stand with computer port, as shown and described.

DESCRIPTION

FIG. 1 is a top, front, left perspective view of a headphone stand with computer port showing our new design;
 FIG. 2 is a top, back, left perspective view thereof;
 FIG. 3 is a front elevational view thereof;
 FIG. 4 is a back elevational view thereof;
 FIG. 5 is a right side elevational view thereof;
 FIG. 6 is a left side elevational view thereof;
 FIG. 7 is a top plan view thereof; and,
 FIG. 8 is a bottom plan view thereof.
 Wherein the broken lines are for illustrative purposes only and form no part of the claimed design.

1 Claim, 4 Drawing Sheets
